UNITED STATES PATENT OFFICE.

ARTHUR A. FULLER, OF PROVIDENCE, RHODE ISLAND, ASSIGNOR TO
HOMER MERIAM, OF SPRINGFIELD, MASSACHUSETTS.

BOOK-HOLDER.

SPECIFICATION forming part of Letters Patent No. 317,937, dated May 12, 1885.

Application filed July 19, 1884. (No model.)

To all whom it may concern:

Be it known that I, ARTHUR A. FULLER, a citizen of the United States, residing at Providence, in the county of Providence and State of Rhode Island, have invented certain new and useful Improvements in Book-Holders; and I do declare the following to be a full, clear, and exact description of the invention, such as will enable others skilled in the art to 5 which it appertains to make and use the same, reference being had to the accompanying drawings, and to letters or figures of reference marked thereon, which form a part of this specification.

15 Figure 1 of the drawings is a representation of this invention and is a perspective view of the back. Fig. 2 is a detail section. Fig. 3 is a detail section. Fig. 4 is a detail view of the under side of the standard.

20 This invention has relation to holders for dictionaries and other books of large size; and it consists in the construction and novel arrangement of devices, as hereinafter set forth, and pointed out in the appended claims.

25 In the accompanying drawings, the letter A designates the stem, the upper portion of which is bored, as at b, to receive the slide B, upon the upper end of which is pivoted a bearing, E, to which the lower leaf of the hinge C is 30 secured by screws.

Around the upper end of the stem A is placed the ring D, which is formed with a threaded perforation, d, which engages a thumb-screw, a', adapted to pass through a perforation, b', in the stem, to engage the slide B, and serving, to hold the latter in position after it has been adjusted to the height desired. A chain, c, connects the ring D to the slide B, and serves to limit the upward movement of 35 the latter, preventing it from being casually drawn out of its socket-way in said stem. The leaf e of the hinge C, being secured to the top of the block-bearing E, rests on the upper end of the slide B. The book-holder is therefore 40 supported on the slide by the hinge-leaf.

In order to prevent the block E from being casually removed from the slide, the bearing in said block through which the slide passes is enlarged at f, and a pin, g, is passed through 45 the upper end of the stem in such a manner

that its ends shall project into the annular enlargement, the pin being removed when it is desired to rotate the block. When the hinge-leaf e is screwed to the block E, the enlargement f and the pin therein are covered securely. 55

To the side of the rotary block E, are secured the short parallel bars F and G, which are provided with a clamp-screw, h, adapted when turned up to draw said bars into closer 60 relation, whereby their frictional engagement with the metallic slide H is increased, said frictional engagement being rendered less by loosening the clamp-screw. k indicates a rearward extension of one of these bars, or a 65 stop, which is designed to limit the angular rise of the book-holder K, which is secured to the upper leaf, e', of the hinge C.

The book-holder K consists of a center board or base, L, having end pieces or flanges, m, to which are pivoted the sides, consisting each of the arms N and the longitudinal bars P, to the inner faces of which are secured the slat-springs S. The lateral edges n of the center-board L are rectangular, and the lower 70 or inner ends of the slat-springs S engage these edges, so that when the sides of the holder are folded upward or toward each other the flat sides of the springs, being pressed against the flat edges of the center board, will 75 hold the sides up or in closed position against the sides of the dictionary or such other large book as may be in the holder. The outer portions, p, of the slat-springs are designed to extend beyond the side bars, P, and to engage 80 the cover-leaves of the back with a yielding pressure. When the book is thrown open, the pivoted sides of the holder are thrown outward and downward, and in this position the inner ends of the slat-springs engage the under 85 surface of the center board.

To the outer faces of the end flanges or transverse end boards, m, are secured the rectangular stops V, the ends of which are engaged by the arms N of the holder when turned up 95 in closed position. When turned downward in open position, these arms N are engaged by the lower faces of the stops V, so that the position of the sides when open is level with the center board. The pivots Z, whereby the 100

arms *N* of the sides are at one end of the holder connected to the end board thereof, are clamp-screws provided with thumb-nuts *v*, which engage a connecting-strip, *z*, of metal, and serve to press said strip against washers *w*, which intervene between said strip and the arms *N*. By turning these thumb-nuts the frictional engagement of the strip and washers with said thumb-nuts and the arms *N* is increased, so that the sides may be held at any angle of inclination with the center board desired; or, by means of these devices, the sides may be fastened in closed or open position. The metallic slide *H* is pivoted to a bearing on the bottom of the book-holder *K*, and, by its frictional engagement with the clamped bars *F* and *G*, it serves to hold the part *K* or book-holder in the angular position to which it has been adjusted.

20 To the lower end of the stem *A* is secured a plate, *J*, having marginal flange-sections *k'*, between which are intervals *g'*, arranged as four equidistant points for the reception of the nicks *k* of the heads *A'* of the four legs *B'*.

25 If a greater number of legs is designed to be used, the flange-sections should correspond in number. The heads *A'* of the legs are flat and have lateral shoulders *s'*, which engage the inner sides of the flange-sections *cn* each side 30 of the intervals *g'*. These heads are somewhat angular in their shape, their inner ends extending toward the center of the plate *J* and being engaged by an under clamping-plate, *I*, which is secured to the lower end of the stem 35 by a clamp-screw, *z'*. When the plate *I* is loosened, the legs may be readily removed.

I am aware that it is not new to provide a book-support with a hinged and vertically-adjustable holder, and that such holders have 40 been provided with means for changing the angular position of the holder, and therefore do not claim such devices, broadly.

Having described this invention, what I claim, and desire to secure by Letters Patent, is—

45

1. The book-holder *K*, consisting of the base or center board, *L*, the lateral arms *N*, pivoted to the center board, and the longitudinal bars *P*, thereto attached, the slat-springs *S*, secured to said longitudinal bars and engaging the 50 edge portions of the center board, and the rectangular end stops, *V*, substantially as specified.

2. The combination, with the end flanges of the holder *K* and the pivoted sides of said holder having slat-springs, of the frictional devices in connection with the pivots of said sides, and the regulating thumb-nuts *v*, substantially as specified.

3. The combination, with the center board, 60 *L*, of the pivoted sides of the holder *K*, having slat-springs adapted to engage the rectangular edge portions of said center board, substantially as specified.

4. The slat-springs *S*, secured to the sides of 65 the book-holder *K*, and projecting at their outer portions, *p*, substantially as specified.

5. The combination, with the stem *A*, of the slide *B* and the pivoted block-bearing *E*, perforated to receive the upper end of said slide, 70 and having the bearing formed by the lower leaf of the hinge-connection *C*, substantially as specified.

6. The combination, with the slide *B* and the holder *K*, of the block-bearing *E*, rotating 75 on said slide, the hinge *C*, the ring *D*, having a thumb-screw, and the chain *e*, substantially as specified.

In testimony whereof I affix my signature in presence of two witnesses.

ARTHUR A. FULLER.
